UNITED STATES PATENT OFFICE.

JAMES A. LYONS, OF FOUNTAIN CITY, TENNESSEE.

CURTAIN-FIXTURE.

SPECIFICATION forming part of Letters Patent No. 739,890, dated September 29, 1903.

Application filed August 29, 1902. Serial No. 121,461. (No model.)

To all whom it may concern:

Be it known that I, JAMES A. LYONS, a citizen of the United States, residing at Fountain City, in the county of Knox and State of Tennessee, have invented a new and useful Improvement in Curtain-Fixtures, of which the following is a specification, reference being had to the accompanying drawings.

My invention relates to window-curtain fixtures, and particularly to that class of window-curtain fixtures in which provision is made for the vertical adjustment of a horizontal spring-actuated roller upon which the curtain or shade is rolled, the object being to secure light and ventilation from above the curtain when desired.

In the accompanying drawings, Figure 1 is a front elevation of a fixture embodying my improvement. Fig. 2 is an end elevation of the construction shown in Fig. 1. Fig. 3 is a plan of a blank from which one of the yoke-brackets is formed. Fig. 4 is a plan of one of said brackets. Fig. 5 is a side elevation of one of said brackets. Fig. 6 is a side elevation of the right-hand upper bracket. Fig. 7 is a front elevation of said bracket. Figs. 8 and 9 are detail views of the combined screw-eye and hook used for securing the guide-cord and for guiding the pull-cord. Figs. 10 and 11 are detail views illustrating the manner of attaching the straps to the upper roller.

Referring to said drawings, 1 is the upper roller, and 10 is the lower or shiftable roller. The latter supports the shade or curtain. (Not shown in the drawings.) Both said rollers are of the common spring-actuated type. At each end the roller 1 is supported in a bracket 2, having its foot 2^a attached to the window-casing A in the usual manner. The upper end of the foot of each of said brackets is preferably turned outward and upward and provided with a V-shaped notch 2^b. A guide-cord 4 is located at each side of the window and secured by its upper end in such notch, said end of the cord being knotted and the knot placed above the foot, the V-shaped notch being so narrow as to prevent the drawing of the knot downward. Each such cord passes downward over the face of the window-casing, the left-hand cord being secured at its lower end in a hook 5 and the lower end

of the right-hand cord being secured in the hook 6^b of the combined screw-eye and hook 6. Said cords may be secured to said hooks in any suitable manner. A simple method is to tie knots into the cord in such position as to be engaged by the hook when the cord lies in the hook and is under the desired tension, the hook being narrower than the thickness of the knot. Said cords serve as vertical guides for the shiftable roller 10.

The combined screw-eye and hook 6 is composed of the eye 6^a and the hook 6^b. Said eye stands in a horizontal plane or in a plane crossing the line in which the adjacent guide-cord lies. The hook 6^b is directed upward toward the upper attachment of said guide-cord, and, as above stated, said hook is preferably narrower than the thickness of a knot in said guide-cord in order that such a knot may be made a means of engaging said hook. The eye 6^a has a twofold function—first, to serve as a means of engagement for turning the screw into the window-casing, and, second, as a guide for the pull-cord, as herein-after described.

Straps or cords 3 are attached by their upper ends to the roller 1 and are adapted to be rolled and unrolled by the rotation of said roller. A yoke 11 is secured to the lower ends of the straps or cords 3. The drawings show said straps or cords extending around said yoke and having the end joined to the main part of the strap or cord by means of a buckle 3^a.

Staples 11^b extend around the strap 3 on the yoke 11 and prevent lateral movement of the straps on the yoke. By raising and lowering the buckles 3^a a precise adjustment of the yoke may be effected. The brackets 11^a support the roller 10 in the usual manner. Said brackets are preferably formed of sheet metal. Fig. 3 shows a sheet-metal blank from which the right-hand bracket is formed. The blank for the left-hand bracket is the same, excepting that it has a slotted aperture for the flat bar of the roller where the right-hand bracket has the round aperture. The part a forms the foot of the bracket, and the part 11^a forms the portion extending across the end of the roller. The part 11^a folds around the bar of the yoke, as clearly shown by the drawings. An eye-pin 11^c ex-

tends through the sleeve 11^d, formed by the folding of the part 11^d of the blank, and through the bar of the yoke lying within said sleeve. Said pin serves to secure said sleeve upon said bar. It also serves to secure the yoke slidably upon the adjacent cord 4, for said cord passes through the eye 11^e of said pin. Upon the left-hand bracket the outer end of said pin is bent rearward to bear upon 5 said sleeve. In the right-hand bracket the upper end of said pin is raised sufficiently to permit attachment of the pull-cord 12.

The weight of the roller 10 and the curtain thereto attached tilts the upper portion of 15 the bracket forward, whereby the avoidance of contact between the rear portion of said pin 11^e and the window-casing is made certain. Thus the cord 4 alone makes contact with the bracket as the latter moves up and 20 down, and scratching of the window-casing is prevented. To reduce friction, the lower end of the bracket-foot is curved outward, as shown in the drawings.

To the right-hand bracket 2 of the upper 25 roller there is applied a spring-hook 2^c. In the form shown this is made by bending spring-wire and securing the ends to said bracket. Said hook is extended downward and toward the window-casing sufficiently to 30 permit the yoke 11 to pass upward above said hook only by pushing said hook outward. When so constructed, the hook reaches beneath said yoke when the latter is at its upper limit, whereby said yoke and the shift- 35 able roller are held against downward movement until said hook is disengaged by being pushed outward away from the window-casing. This is accomplished by means of the hinged stirrup 12^a on the yoke. Said stirrup 40 consists of a wire extending parallel to the adjacent sleeve 11^d and having its ends in-turned and extending into said sleeve and the bar of the yoke, as shown by the drawings, whereby said stirrup is hinged. The 45 relative arrangement and dimensions of these parts are such as to leave said stirrup and said spring-hook out of engagement when said stirrup is free to turn toward the window-casing, but to cause said stirrup to en- 50 gage and lift said spring-hook when said stirrup is rotated away from the window-casing. The pull-cord 12 and said stirrup are ar- 55 ranged in such relation as to cause said pull-cord to lift said stirrup when said cord is pulled for the purpose of drawing the yoke and shiftable roller downward. As shown in the drawings, the pull-cord is attached to the upper portion of the eye-pin 11^e and extends thence downward over the front face of the 60 yoke and thence rearward through the stir- 65 rup 12^a and thence downward through the eye of the combined screw-eye and hook 6. It will be readily seen that drawing said pull-cord will tend to straighten said cord, where- 65 by said stirrup is thrown forward. If the spring-hook is then resting against said stir- rup, it will be lifted by the latter. When

the spring-hook has thus been lifted, the yoke is free to descend by continued pulling on the pull-cord.

It is not essential to pass the pull-cord through the eye at 6; but it is a matter of convenience to insure a definite direction of movement for said cord.

On the right-hand end of the roller 1 is lo- 75 cated a locking-lug 1^a, the function of which is to prevent the rotation of the roller 1 so long as the right-hand end of the yoke-bar is in its upper position. Said locking-lug is so placed as to bear upon the upper face of the 80 yoke when the latter is at its upper limit. The purpose of this lug is to prevent the de- 85 scence of the left-hand portion of the yoke and shiftable roller (when draft is put upon the curtain to unroll the latter from the shiftable roller) while the right-hand portion of said yoke and roller are held by the spring-hook 2^c. It will be observed that the left-hand portion of said yoke cannot descend without drawing down the left-hand strap 3, and the 90 latter cannot be drawn down without rotat- 95 ing the roller 1, and, as already explained, the roller 1 is locked against rotation by the bearing of the locking-lug 1^a upon the upper face of the yoke. With this construction a lighter spring may be used in the upper roller.

I have found it desirable to so attach the straps 3 to the upper roller as to prevent them from being torn off. An effective method is illustrated by Figs. 10 and 11. The upper end 100 of the strap is passed through an elongated metallic eye and laid over upon itself and se- 105 cured to the roller by a tack 3^c. From said tack this strap passes around the roller and again through said eye and thence downward 110 to the yoke. It will be observed that the strap can unroll only as far as said eye, and when it has unrolled that far the draft is upon the eye and the strain is resisted by the fric- 115 tion of the strap on the eye and around the 120 roller and again on the eye and again upon a portion of the exterior of the roller.

Within the sleeve 11^d the lower face of the yoke-bar should be suitably channeled to 125 make a bearing for the inturned ends of the stirrup 12^a, and provision should be made for limiting the upward movement of said stir- 130 rup in order that said stirrup may never rise so high as to allow the spring-hook to enter beneath said stirrup while the yoke is mov- 135 ing upward. For this purpose some suitable stop should be provided upon the yoke. This may be conveniently accomplished by cut- 140 ting out the sleeve to only a limited extent at the point 12^b, Fig. 3, where the left-hand in- 145 turned end of the stirrup extends into said sleeve.

I claim as my invention—

1. In a curtain-fixture, the combination with a stationary roller, a shiftable roller, a 130 yoke supporting said shiftable roller and straps uniting said yoke and said stationary roller, of means for locking said yoke in its upper position and means supported by said

stationary roller for engaging said yoke and locking said upper roller against rotation while said yoke is at its upper limit.

2. In a curtain - fixture, the combination with a stationary roller, a shiftable roller, a yoke supporting said shiftable roller, straps uniting said yoke and said stationary roller, of a lug on said upper roller adapted to bear against said yoke while the latter is at its upper limit.

3. In a curtain - fixture, the combination with a stationary roller, a shiftable roller, a yoke supporting said shiftable roller, straps uniting said yoke and said stationary roller, of a spring-hook for engaging said yoke while the latter is at its upper limit and a lug on said upper roller arranged to bear upon said yoke while the latter is at its upper limit.

4. In a curtain - fixture, the combination with an upper stationary roller, a lower shiftable roller, a yoke supporting said shiftable roller, and straps connecting said yoke and the upper roller, of a spring-hook, 2°, located adjacent to the upper roller, a stirrup, 12^a, applied to said yoke, and a pull-cord applied to said yoke and stirrup.

5. In a curtain - fixture, the combination with an upper stationary roller, a lower shiftable roller, a yoke supporting said shiftable roller, and straps connecting said yoke and the upper roller, of a spring-hook, 2°, located adjacent to the upper roller, a stirrup, 12^a, applied to said yoke, a pull-cord applied to said yoke and stirrup, and means for locking said upper roller against rotation while said yoke is at its upper limit.

6. In a curtain - fixture, the combination of a yoke, 11, sleeve, 11^d, and stirrup, 12^a, having inturned ends extending into said sleeve.

40 7. In a curtain - fixture, the combination of a yoke, 11, sleeves, 11^d, eye-pins, 11^c, and guide-cords, 4, extending through the eyes of said eye-pins.

8. In a curtain - fixture, the combination of 45 an upper roller, brackets for supporting said

roller, said brackets having feet, the upper ends of which are outwardly turned and notched, guide-cords secured by their upper ends in said notches and by their lower ends to a fastening device supported from the window-casing.

5 9. In a curtain - fixture, the combination with a vertically-shiftable yoke and curtain-roller supported by said yoke, a guide-cord for guiding said roller, and means for securing the upper end of said cord, of a combined screw-eye and hook, the eye of said combined screw-eye and hook being in a plane parallel with the screw-shank and in a plane to which said cord is perpendicular, and said hook being directed upward and engaging said cord, and a pull-cord applied to said yoke and extending through said eye.

55 10. In a curtain - fixture, the combination of an upper stationary roller, a lower shiftable roller, a yoke for supporting said shiftable roller, straps extending from said yoke upward and through elongated eyes adjacent to the upper roller, thence around said upper roller and again through said elongated eye and backward along said strap, and there terminating, said terminating portion being suitably secured.

60 11. In a curtain - fixture, the combination with an upper stationary roller, a lower shiftable roller, a yoke supporting said shiftable roller, and straps connecting said yoke and the upper roller, of a spring-hook, 2°, located adjacent to the upper roller, a stirrup, 12^a, applied to said yoke by a hinge permitting limited movement, and a pull-cord applied to said yoke and stirrup.

65 In testimony whereof I have signed my name, in presence of two witnesses, this 25th day of August, in the year 1902.

JAMES A. LYONS.
